GRID FOR DRUM FILTER

John E. Krynski, East Moline, Ill., assignor to Ametek,
Inc., New York, N.Y., a corporation of Delaware

Filed July 31, 1962, Ser. No. 71,116

Term of patent 14 years

(Cl. D55—1)

Des. 201,390

PAGE 2

FIG. 3

FIG. 4

FIG. 1 is a fragmentary perspective view of a grid for a drum filter;

FIG. 2 is an enlarged fragmentary view of FIG. 1;

FIG. 3 is a plan view of a modified form of the grid shown in FIG. 1; and

FIG. 4 is a reduced view of the grid of FIG. 1 shown on a drum filter, said drum filter and other grids shown in broken lines for illustrative purposes.

I claim:

The ornamental design for a grid for drum filter, substantially as shown and described.
